ABSTRACT OF THE DISCLOSURE

Pharmaceutical compositions characterized by circulatory stimulating and saluretic activity comprising 2-methyl-4-hydroxy-pyrido-[2,3-d]-pyrimidine in admixture with a pharmaceutical carrier.

The present invention relates to novel pharmaceutical compositions characterized by circulatory stimulating and saluretic activity and to methods for using the same.

2-methyl-4-hydroxy-pyrido-[2,3-d]-pyrimidine has been described by Klisiecki et al. (Roczniki Chem., 3, 251-256/1923). However, its use as a pharmacological agent has not been suggested or investigated.

It is known that some pyrido-pyrimidine derivatives having somewhat similar structures are antagonists of folic acid and of the nucleic acids and can be used effectively as diuretics and bactericides. Closely analogous pyrido-pyrimidines are characterized by central nervous depressive and hypnotic properties, i.e. in their action, they resemble the known hypnotic methaqualone hydrochloride from which they differ merely by the substitution of a carbon atom by a nitrogen atom (Indian J. Chem., 4, 447/1966).

In accordance with the invention it has now, surprisingly been found that 2-methyl-4-hydroxy-pyrido-[2,3-d]-pyrimidine not only possesses excellent saluretic properties but also outstandingly good circulatory stimulating properties.

Almost without exception, the previously commercially available circulatory stimulants are sympathomimetics. The broadest fields of use of sympathomimetically-acting pharmaceuticals are in the regulation of constitutional hypotonic disturbances. Since, however, the known sympathomimetics only have a relatively short period of activity, it is necessary to prolong the duration of activity by the use of special pharmaceutical depot formulations.

2-methyl-4-hydroxy-pyrido-[2,3-d]-pyrimidine is characterized by a surprisingly long period of activity so that it is no longer necessary to utilize this compound in the form of a depot formulation.

Furthermore, it has been established, and this is to be considered extremely advantageous, that 2-methyl-4-hydroxy-pyrido-[2,3-d]-pyrimidine, in contradistinction to the known sympathomimetics, such as adrenaline or noradrenaline, brings about, parallel, i.e., simultaneously with an increase in the heart minute volume and an increase in the flow of blood through the kidneys, a considerable increase in natriuresis without, however, influencing the excretion of potassium.

Thus according to the present invention, there are provided pharmaceutical compositions having circulatory stimulating and saluretic activity which contain, as active ingredient, 2-methyl-4-hydroxy-pyrido-[2,3-d]-pyrimidine,

in admixture with a pharmaceutical carrier. The latter can be either a solid pharmaceutical carrier or diluent when intended for oral administration, or as a suppository, or a sterile injectable liquid pharmaceutical carrier or diluent, when intended for intravenous, intraarterial or parenteral administration, or a liquid pharmaceutical carrier or diluent possibly in admixture with a sweetening and/or flavoring agent, when intended for oral administration.

10 The pharmaceutical compositions according to the present invention can be utilized in any of the forms as conventionally used for oral or parenteral administration, such as tablets, dragees, capsules, syrups, solutions, suspension, drops, suppositories or the like. For this purpose, the active compound is mixed with appropriate liquid or solid carriers or diluents and then made up into the desired form of administration by any of the conventional techniques employed in the art.

15 As examples of solid carriers or diluents, there may be mentioned lactose, mannitol, starch, talc, methylcellulose, magnesium stearate and gelatine, to which, if desired, there can be added coloring materials and/or flavoring agents and/or sweetening agents. As mentioned above, when the compositions are intended to be used as injection solutions, they must be sterile and are advantageously used in the form of ampoules.

20 The preferred liquid carrier is water, preferably containing at least one stabilizer and/or solubilizer and/or buffer and/or viscosity regulator. Additives of this type include buffers, such as a tartrate or citrate buffer, solubilizers, such as ethanol, stabilizers, such as complex-forming agents, for example, ethylene-diamine-tetraacetic acid and its non-toxic salts, and viscosity regulators, such as high molecular weight polymers, for example, liquid polyethylene oxide.

25 In the case of the treatment of human beings, 2-methyl-4-hydroxy-pyrido-[2,3-d]-pyrimidine is usually administered orally at a dosage level of 10-200 mg. and intravenously at a dosage level of 5-100 mg. In these dosage ranges, besides an optimum saluretic action, there is also achieved a sufficient hypertonic action and a positive inotropic action. As the active material is orally well resorbed, intravenous administration is only preferred in those cases in which a rapid increase in blood pressure is required or in which, for other reasons, oral administration of medicaments is contraindicated.

30 The administration of the 2-methyl-4-hydroxy-pyrido-[2,3-d]-pyrimidine-containing compositions according to the present invention is especially indicated in cases of hypotonic regulation disturbances in which it is desired to obtain a long-lasting increase of the blood pressure and, also at the same time, an increase in the flow of blood through the kidneys.

35 In order to unequivocally demonstrate the circulatory-stimulating and saluretic activity of 2-methyl-4-hydroxy-pyrido-[2,3-d]-pyrimidine, the following pharmacological experiments were carried out.

60 (I) CIRCULATORY STIMULATION IN DOGS

(1) Blood pressure and heart rate of awake normotonic dogs

65 *Method.*—4 beagles, each having a weight of 8-15 kg. were used as experimental animals. Catheters were introduced via the arteria or vena femoralis into the abdominal aorta or into the caudal cavity vein and there implanted. 10 mg./kg. 2 - methyl-4-hydroxy-pyrido-[2,3-d]-pyrimidine, dissolved in physiological saline, were then intravenously injected into the dogs in a total amount of

TABLE II—Continued

Peripheral resistance in percent

Dog No.:	Time																			
	Infusion		Time																	
	Start	End	5	10	5	15	30	60	90	120	150	180	210	240	270	300	330	360		
	K	mins.	mins.	mins.	mins.	mins.	mins.	mins.	mins.	mins.	mins.	mins.	mins.	mins.	mins.	mins.	mins.	mins.	mins.	mins.

50-----	100	106	116	98	95	94	89	93	86				105							
Average... .	100	109	99	107	102	113	109	124						117						

NOTE.—In the above II, K=control value.

Results:—The alterations of the heart minute volume fall within the range of error of the method. As the most noticeable action of 2-methyl-4-hydroxy-pyrido-[2,3-d]-pyrimidine on the circulation, there is observed a gradual increase of the average blood pressure. Furthermore, there is observed an increase of the peripheral resistance of the order of about 30% and a decrease of heart beat volume of the same order. The heart rate increases up to the end of the experiment by about 20–30 beats per minute. If an attempt is made to find a relationship between these circulatory parameters, then it is obvious to assume that the increase of pressure can be attributed to an increase in the peripheral resistance. It was to have been expected that in the case of a pressure increase in the dog, a corresponding decrease of the minute volume and of the heart rate would follow. Surprisingly, however, there is observed an increase of rate, as well as an unchanged heart minute volume. Thus

15 **Results:**—After only 2 hours had elapsed, there was observed a constant potassium excretion but a marked natriuretic effect, which is also expressed in the Na/K quotient. Simultaneously with the natriuresis, the volume of urine increases by a factor of about 2. When a dosage of 12.0 mg./kg. was used, the diuretic and natriuretic action is optimal and, in the case of higher dosages, gradually decreases again. Within a period of 6 hours, the diuresis has increased by a factor of 3, while no significant alterations were observed in the Na/K quotients.

20 25 (b) Using oral administration

Method:—2-methyl-4-hydroxy-pyrido-[2,3-d]-pyrimidine was administered in the same form as described above in II(1a) but via the oral route. The results which were obtained are set out in Table IV which follows:

TABLE IV.—INFLUENCE ON THE EXCRETION OF URINE AND ELECTROLYTES IN RATS—ORALLY
[n=number of groups each of 5 rats]

Dosage, mg./kg.	Excretion/kg. in the course of—										
	2 hours					6 hours					
	n	mVal			Na/K	ML urine	mVal			Na/K	
		Cl	Na	K			Cl	Na	K		
Control.....	9	7.0	0.1	0.1	0.2	0.5	10.2	0.3	0.3	0.6	0.5
3.0.....	6	6.0	0.1	0.1	0.2	0.5	10.4	0.4	0.4	0.7	0.6
6.0.....	6	10.5	0.4	0.4	0.3	1.3	19.8	1.3	1.1	0.9	1.2
12.0.....	6	11.0	1.1	1.1	0.2	6.0	36.4	4.0	4.2	0.7	6.0
25.0.....	6	6.7	0.9	0.9	0.1	9.0	21.1	2.9	2.9	0.6	4.8

it is established that 2-methyl-4-hydroxy-pyrido-[2,3-d]-pyrimidine has a positive chronotropic and a positive inotropic action.

(II) INFLUENCE ON THE EXCRETION OF URINE AND ELECTROLYTES

(1) Experiments on rats.—(a) Using intraperitoneal administration

Method:—Female Sprague-Dawley rats each having an average weight of 160 g. were maintained in the fasting condition overnight but were allowed an unlimited amount of drinking water. 2-methyl-4-hydroxy-pyrido-[2,3-d]-pyrimidine in an 0.5% tylose suspension (10 ml./kg.) was then administered intraperitoneally. After 2 hours had elapsed and again after 6 hours had elapsed, the animals' bladders were pressed out and the volume of urine, as well as the electrolyte excretion, determined. The results of this experiment are described in Table III which follows:

TABLE III.—INFLUENCE ON THE EXCRETION OF URINE AND ELECTROLYTES IN RATS—INTRAPERITONEALLY
[n=number of groups each of 5 rats]

Dosage, mg./kg.	Excretion/kg. in the course of—										
	2 hours					6 hours					
	n	mVal			Na/K	ML urine	mVal			Na/K	
		Cl	Na	K			Cl	Na	K		
Control.....	6	5.9	0.01	0.03	0.2	0.2	9.1	0.3	0.2	0.6	0.3
1.5.....	6	5.0	0.04	0.03	0.2	0.2	7.4	0.3	0.2	0.7	0.3
3.0.....	6	6.2	0.1	0.1	0.2	0.5	9.4	0.3	0.3	0.6	0.5
6.0.....	6	9.0	0.4	0.4	0.2	2.0	20.3	1.6	1.3	0.8	1.6
12.0.....	6	9.7	1.0	1.0	0.2	5.0	28.4	3.2	3.0	0.6	5.0
25.0.....	6	5.7	0.7	0.8	0.1	6.0	23.9	2.9	3.1	0.5	6.2

45 **Results:**—The experiment results which were obtained corresponded substantially to those obtained in the case of intraperitoneal administration. From this, there can be appreciated that the compound is excellently orally resorbed.

50 55 (2) Experiments on dogs.—(a) Using intravenous administration

Method:—Female beagles each having an average weight of 11.8 kg. were maintained in the fasting state overnight but allowed an unlimited supply of drinking water. 2-methyl-4-hydroxy-pyrido-[2,3-d]-pyrimidine was injected intravenously at a rate of 1 ml./kg. of an 0.5% glucose solution. After 2 hours had elapsed and again after 6 hours had elapsed, the urine was obtained directly from the bladder by means of a catheter, measured and analyzed for its electrolyte content.

(b) Using oral administration

Method:—2 - methyl - 4 - hydroxy - pyrido - [2,3 - d] - pyrimidine was administered in the same manner as described in II(2a) but orally and in the form of an 0.5% tylose suspension thereof at a rate of 1 ml./kg. The results which were obtained are set out in Table V which follows:

TABLE V.—INFLUENCE ON THE EXCRETION OF URINE AND ELECTROLYTES IN DOGS

[n=number of dogs in the group]

Dosage, mg./kg.	n	Route of adminis- tration	Excretion/kg. in the course of—						
			2 hours			6 hours			
			MI.	m Val	Cl	MI.	m Val	Cl	
Control	8	p.o.	2.2	0.1	0.04	0.1	4.3	0.1	0.1
10	5	p.o.	1.5	0.1	0.2	0.1	4.3	0.4	0.6
25	6	p.o.	1.8	0.2	0.3	0.1	6.3	0.8	1.1
Control	17	i.v.	1.9	0.1	0.1	0.1	5.6	0.3	0.4
7	6	i.v.	2.9	0.1	0.2	0.1	11.1	0.3	0.6
10	6	i.v.	2.7	0.2	0.3	0.1	17.8	1.0	1.1

Results:—Exactly as in the case of rats, in the case of dogs, there is observed a marked increase of natriuresis, of diuresis and of the Na/K quotients, whereas the kaliuresis was not affected.

(III) ACUTE TOXICITY

Method:—The acute toxicity was determined on NMRI mice each having an average weight of 20 g. The LD₅₀ was determined following a complete probit analysis. For this purpose, the 2-methyl-4-hydroxy-pyrido-[2,3-d]-pyrimidine was administered as follows:

- (A) orally in 1% tylose;
- (B) intraperitoneally in water;
- (C) intravenously in 0.9% sodium chloride solution.

The results which were obtained are set out in Table VI which follows:

TABLE VI

Route of administration:	Average lethal dose (LD ₅₀) mg./kg.
P.o.	124
I.p.	284
I.v.	204

The following examples are given for the purpose of illustrating the present invention but are in nowise to be construed as a limitation thereof.

EXAMPLE 1

Ampoule formulation

10 mg. 2-methyl-4-hydroxy-pyrido-[2,3-d] -pyrimidine were dissolved in 1 ml. double distilled water, filled into white ampules and sterilized by heating for 20 minutes at 120° C.

10 mg. 2-methyl-4-hydroxy-pyrido-[2,3-d]-pyrimidine were dissolved in 1 ml. double distilled water, filled into white ampules and sterilized by heating for 20 minutes at 120° C.

EXAMPLE 2

Ampoule formulation

50 mg. 2-methyl-4-hydroxy-pyrido-[2,3-d]-pyrimidine were dissolved in 2 ml. double distilled water, filled into white ampoules and sterilized by heating for 20 minutes at 120° C.

EXAMPLE 3

Tablet formulation

	Mg.
2-methyl-4-hydroxy-pyrido-[2,3-d]-pyrimidine	20.0
Lactose	52.5
Maize starch	52.5
Methyl cellulose	7.0
Talc	7.0
Magnesium stearate	1.0
	140.0

2 - methyl - 4 - hydroxy - pyrido - [2,3 - d] - pyrimidine was mixed with lactose and maize starch and the mixture granulated with a 10% maize starch paste. The granulate thereby obtained was passed through a sieve having a mesh size of 0.8 mm. Thereafter, the methyl cellulose, talc and magnesium stearate were added to the granulate. The resultant mixture was homogenized and pressed into tablets having a diameter of 7.0 mm. and a total weight of 140 mg.

EXAMPLE 4

Tablet formulation

	Mg.
2-methyl-4-hydroxy-pyrido-[2,3-d]-pyrimidine	100
Lactose	75
Maize starch	75
Methyl cellulose	14
Talc	14
Magnesium stearate	2
	280

The components as above set out were mixed together according to the procedure described in Example 3, the mixture homogenized and then pressed into tablets having a diameter of 10.0 mm. and a total weight of 280 mg.

What is claimed is:

1. A pharmaceutical composition for use in stimulating circulatory and saluretic activity comprising, in effective amounts, 2 - methyl-4-hydroxy-pyrido-[2,3-d]-pyrimidine and a pharmaceutically acceptable liquid carrier.
2. A pharmaceutical composition according to claim 1 additionally containing at least one member selected from the group consisting of solubilizers, stabilizers, buffers and viscosity regulators.
3. A pharmaceutical composition according to claim 2 wherein said solubilizer is ethanol.
4. A pharmaceutical composition according to claim 2 wherein said stabilizer is a complex forming agent.
5. A pharmaceutical composition according to claim 2 wherein said buffer is a member selected from the group consisting of citrate and tartrate buffers.
6. A pharmaceutical composition according to claim 2 wherein said viscosity regulator is liquid polyethylene oxide.
7. A pharmaceutical composition according to claim 1 additionally containing a coloring agent.
8. A tablet comprising a pharmaceutical composition according to claim 1 in dosage unit form.
9. A pharmaceutical composition according to claim 8 adapted for oral administration.
10. A pharmaceutical composition according to claim 9 comprising a tablet containing 10 to 200 mg. of said 2-methyl-4-hydroxy-pyrido-[2,3-d]-pyrimidine.
11. A pharmaceutical composition according to claim 9 comprising a dragee of said 2-methyl-4-hydroxy-pyrido-[2,3-d]-pyrimidine.
12. A pharmaceutical composition according to claim 9 comprising a capsule containing 10 to 200 mg. of said 2-methyl-4-hydroxy-pyrido-[2,3-d]-pyrimidine.
13. A pharmaceutical composition for stimulating circulatory and saluretic activity comprising an effective amount of 2-methyl-4-hydroxy-pyrido-[2,3-d]-pyrimidine in admixture with a solid pharmaceutical carrier.

14. A sterile injectible liquid pharmaceutical composition for use in stimulating circulatory and saluretic activity comprising effective amounts of 2-methyl-4-hydroxy-pyrido-[2,3-*d*]-pyrimidine.

15. An ampoule containing a composition as claimed in claim 14.

16. Composition as claimed in claim 15 wherein the composition also contains at least one of a coloring, sweetening and flavoring agent.

17. Method of treating hypotonic regulation disturbances and simultaneously obtaining an increase of blood flow through the kidneys which comprises administering to a mammal in which such treatment is indicated as composition containing therapeutically effective amounts of 2-methyl-4-hydroxy-pyrido-[2,3-*d*]-pyrimidine.

18. Method according to claim 17 comprising orally

administering said composition containing 10-200 mg. of said 2-methyl-4-hydroxy-pyrido-[2,3-*d*]-pyrimidine.

19. Method according to claim 17 comprising parenterally administering said composition containing 5-100 mg. of said 2-methyl-4-hydroxy-pyrido-[2,3-*d*]-pyrimidine.
